UNITED STATES PATENT OFFICE.

EBENEZER A. W. JEFFERIES, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

GAS-PRODUCER.

1,251,039.

Specification of Letters Patent. Patented Dec. 25, 1917.

Original application filed August 2, 1913, Serial No. 782,561. Divided and this application filed December 16, 1914. Serial No. 877,488.

To all whom it may concern:

Be it known that I, EBENEZER A. W. JEFFERIES, a citizen of the United States, residing at Worcester, in the county of Worcester and Commonwealth of Massachusetts, have invented a new and useful Improvement in Gas-Producers, of which the following, together with the accompanying drawings, is a specification.

10 The present invention relates to gas producers, and has particular reference to the provision of means for evening or smoothing the surface of the bed of fuel in a gas producer, and for agitating said surface to prevent both the caking of the fuel by fusion, and the formation of openings, or pipes, through the mass of the same. The subject-matter of the invention is shown and described in my co-pending application 15 Serial No. 782,561, filed August 2, 1913, of which the present application is a division.

The efficient operation of a gas producer is, to a great degree, dependent upon the maintenance in the combustion chamber 25 thereof, of a bed of fuel substantially homogeneous in character and of uniform thickness throughout, whereby the blast of air, or air and steam, which is forced through the fuel to support the combustion thereof, may 30 permeate the same uniformly and thoroughly, in order to keep the combustion uniform. The ordinary methods of feeding fuel to a gas producer, through a hopper, or the like, contribute naturally to the formation of a more or less uneven bed of fuel upon the grate. As a result, the combustion of such fuel tends to render the fuel bed solid and substantially impenetrable in some portions, while other portions become 35 more or less cellular in character. By reason of the unequal distribution of the blast, and the nonuniformity of the combustion, under these conditions, the quality and quantity of the gas generated by the producer is 40 seriously impaired.

The present invention provides a means for overcoming the above described difficulties of operation, whereby the generation of gas is carried on at the maximum efficiency, and without substantial variation in quantity. The apparatus constituting my invention is fully set forth in the following

description, reference being had to the accompanying drawings, in which—

Figure 1 is a vertical sectional view of 55 so much of a gas producer as is necessary to disclose my invention.

Fig. 2 is a fragmentary side view of the same.

Similar reference characters refer to similar parts in both figures.

The gas producer shown in the drawings comprises a fuel containing section 1, which is supported by any suitable devices, not shown, to permit of its rotation, by means of an annular rack 2 and a worm 3. The wall of section 1 provides an annular water chamber 4, open at the top. Communicating with the section 1, and concentric therewith, the producer has a stationary 70 upper section 5, supported in any convenient manner, not shown, and having a depending apron 6 which extends below the level of the water in chamber 4 to provide a seal against the escape of gases from the 75 gas chamber inclosed by said sections. The top of section 5 is closed by a cover plate 7, preferably provided with means for supporting a body of water, to prevent overheating. The cover plate 7 has an opening 80 8 for the introduction of fuel to the section 1; and said plate supports a hopper or fuel feeding device 9 in operative position with respect to opening 8 and having means, consisting of an annular apron 10, for forming a water seal against the escape of gases 85 through said opening. The stationary section 5 also has a suitable outlet opening, not shown, for the delivery of the gases generated by the combustion of fuel within the 90 section 1.

The wall of section 5, near its lower end, is provided, in opposite sides, with aligned openings, for the reception of a pair of bearing castings 11, 11, which are preferably 95 maintained cool by the circulation of water through their hollow portions 12. Alined bearing apertures extending through said castings 11 provide for the pivoting of the opposite ends 13, 13 of an elongated member 14, in the form of a pipe or tube, the central portion of which is offset from the pivotal axis of the ends 13, as shown in Fig. 1, forming in effect a connection between two par-

allel crank arms 15. Said central or cranked portion, which is capable of swinging freely about the horizontal axis afforded by its ends 13, 13, rests, by gravity, upon the surface 5 of the fuel bed in the section, causing the crank arms 15 to lie at an incline, as shown in Fig. 2. The axis of the bearings 11, 11 may, if desired, coincide with a diameter of the producer; preferably, however, 10 said axis is slightly offset from a diameter of the producer in order that the cranked or central portion of the member 14, may, when the mean level of fuel in section 1 is at an average height, make contact with the 15 same at or near a diameter of the producer.

Flexible inlet and outlet pipes 16 and 17, connected to the ends 13 of the tubular member 14, provide for a circulation of water therethrough to prevent undue heating of 20 the portions which are subject to severe heat within the producer. One of the ends 13 of member 14 carries, beyond the wall of section 5, an arm 18, the same being securely attached by means of a clamp 19, providing 25 for the fixing of said arm at any desired angle with reference to the pivotal axis of member 14. The arm 18 carries an adjustable weight 20, movable toward and from the said pivotal axis to vary the pressure of 30 the crown, or cranked portion of member 14 against the surface of the fuel. A rod 21, pivotally connected at 22 to the arm 18, extends loosely through a standard 23, and has threaded on its upper end, beyond said 35 standard, a hand wheel 24.

In the operation of the producer, the horizontal cranked portion of the member 14 rests upon the surface of the fuel in a diametrical, or nearly diametrical, position, dependent 40 upon the level to which the fuel has risen in the section 1. The constant rotation of the section 1 brings every portion of the surface of the fuel bed under the influence of said member, thereby effecting the 45 desired agitation of said surface, and leveling and smoothing the same to render the bed of fuel homogeneous throughout and of uniform thickness. It is obvious that the pressure exerted upon the fuel by the member 50 14 is dependent upon the leverage of the weight 20; and that this leverage, determined by the horizontal distance of said weight from the axis of the bearings 11, may be varied by sliding the weight along 55 the arm 18, or by changing the angular position of said arm.

As the thickness of the fuel bed varies, and its surface rises and falls, it is apparent that the member 14 will adjust itself to the 60 changing conditions, owing to the support of the cranked portion of said member upon the surface of the fuel. Said cranked portion will be caused to move freely in a circular arc about the pivotal axis of the ends 65 13, the radius of said arc being the length

of the crank arms 15. The vertical component of said circular movement coincides with the change in the mean height of the fuel bed, as will be apparent.

The swinging of the member 14, in response to changes in the thickness of the fuel bed, moves the rod 21 through the standard 24. By adjusting the hand wheel 23 inwardly upon said rod, so as to engage with the upper end of said standard, the downward swinging movement of the member 14 may be limited, and as a consequence, the said member may be prevented from digging too deeply into the surface of the fuel.

1. claim—

1. In a gas producer, means for supporting a bed of fuel, a member pivoted at one end about a horizontal axis lying above said bed, and resting by gravity at its other end on the surface of said bed whereby said other end rises and falls in response to changes in thickness of said bed, and means for causing relative traversing movement between said bed and said member.

2. In a gas producer, means for supporting a bed of fuel, a pivotally suspended member having its free end resting by gravity on the surface of said bed, whereby said free end rises and falls in response to changes in the thickness of said bed, and means for causing a relative traversing movement between said bed and said member.

3. In a gas producer, a fuel section, fuel evening means within said fuel section comprising a pivoted member adapted to contact with the surface of the fuel in said section, means for supporting said member to adjust itself to the level of the fuel in said section, and means for causing a relative traversing movement between the surface 105 of the fuel and said member.

4. In a gas producer, a fuel section, a pivoted fuel evener within said fuel section automatically movable in response to changes in the level of the fuel within said section, and means for causing relative traversing movement between said evener and the surface 110 of the fuel.

5. In a gas producer, means for supporting a bed of fuel, an element operative with respect to the surface of said bed for smoothing and evening the same, means for pivotally supporting said element for vertical self-adjustment in response to changes in the level of said bed, and means for causing a relative traversing movement between said bed and said member.

6. In a gas producer, means for supporting a bed of fuel, means for feeding fuel to said bed during the operation of the producer, a fuel evener resting by gravity on the surface of said bed, and adapted to adjust itself to changes in the thickness of said bed, means for varying the pressure of said fuel evener against the surface of said bed,

and means for causing relative traversing movement between said fuel evener and said bed.

7. In a gas producer, a fuel section, a pivoted member having its free end supported by the surface of the fuel in said fuel sections, means for varying the pressure of said free end against the surface of said fuel, and means for causing relative traversing movement between said member and the surface of the fuel.

8. In a gas producer, means for supporting a bed of fuel, means for feeding fuel to said bed during the operation of the producer, fuel evening means effective with respect to the surface of said bed and resting by gravity thereon, means for constraining the vertical movement of said means about a fixed axis in response to changes in the thickness of said bed, and means for effecting a relative traversing movement between said fuel evening means and the surface of said bed.

9. In a gas producer, fuel evening means in contact with the surface of the fuel bed, said means being movable in a circular arc in response to changes in the thickness of said bed, and means for causing relative traversing movement between said bed and said fuel evening means.

10. In a gas producer, fuel evening means in contact with the surface of the fuel bed, and movable in a circular arc in response to changes in the thickness of said bed, the vertical component of such movement corresponding to the change in the level of said bed, and means for causing relative traversing movement between said bed and said fuel evening means.

11. In a gas producer, a fuel section, a U-shaped fuel evener resting by gravity on the surface of the fuel bed with the ends of its arms turned outwardly and pivoted in horizontal bearings to allow its lower portion to swing into contact with the surface of the fuel in the fuel section, and means for causing relative rotation between the fuel section and the evener to cause the evener to move along the surface of the fuel.

12. In a gas producer, a fuel section, a U-shaped fuel evener with the ends of its arms turned outwardly and pivoted in horizontal bearings to allow its central portion to swing into contact with the surface of the fuel in the fuel section, a lever extending laterally from the evener, a weight carried by the lever to increase the pressure of the evener upon the surface of the fuel, and means for causing relative rotation between the fuel section and the evener to cause the evener to move over the surface of the fuel.

13. In a gas producer, a fuel section, a U-shaped fuel evener resting by gravity on the surface of the fuel bed with the ends of its arms turned outwardly and pivoted in horizontal bearings to allow its central portion to

swing into contact with the surface of the fuel in the fuel section, means to limit the swing of the evener toward the fuel, and means for causing relative rotation of the fuel section and the evener to cause the evener to move along the surface of the fuel.

14. In a gas producer, means for supporting a bed of fuel, means for feeding fuel to said bed during the operation of the producer, a fuel evener effective with respect to the surface of said bed and adapted to adjust itself to the level assumed by said surface, and means for varying the pressure of said fuel evener against the surface of said bed.

15. In a gas producer, a fuel section, means for feeding fuel to said fuel section during the operation of the producer, a pivoted member having its free end supported by the surface of the fuel in said fuel section, and means for varying the pressure of said free end against the surface of said fuel.

16. In a gas producer, means for supporting a bed of fuel, means for feeding fuel to said bed during the operation of the producer, fuel evening means effective with respect to the surface of said bed and resting by gravity thereon, means for constraining the vertical movement of said means about a fixed axis as the level of the bed of fuel rises and falls, and means for effecting a relative traversing movement between said fuel evening means and the surface of said bed.

17. In a gas producer, means for supporting a bed of fuel, a member pivoted at one end about a horizontal axis above said bed, and resting by gravity at its other end on the surface of said bed, and means for causing relative movement between said bed and said member.

18. In a gas producer, means for supporting a bed of fuel, a pivotally suspended member having its free end resting by gravity on the surface of said bed, and means for causing a relative traversing movement between said bed and said member.

19. In a gas producer, means for supporting a bed of fuel, a fuel evening means in contact with the surface of said bed and having a substantially diametrical disposition with respect to said surface, said fuel evening means being movable in a circular arc in response to changes in the thickness of said bed, and means for causing a relative traversing movement between said bed and said fuel evening means.

20. A gas producer comprising a shell adapted to contain a fuel bed, a swinging charge-agitating member extending through said shell into the fuel bed and constructed to automatically adjust itself to the height of said bed, and means for effecting relative rotary motion between said fuel bed and member.

21. A gas producer comprising a shell

adapted to contain a fuel bed, a substantially U-shaped charge-agitating member extending through said shell into the fuel bed and constructed to automatically adjust itself to the height of said bed, and means for effecting relative rotary motion between said fuel bed and member.

22. A gas producer having means for feeding fuel thereto, during the operation of the producer, having an agitator playing freely vertically in operation, means exerting downward pressure on the agitator and means causing relative horizontal travel between the agitator and the coal while gas is being produced therein.

23. A gas producer having a vertically

swinging agitator playing freely and means causing relative horizontal travel between the agitator and the coal.

24. A gas producer having means for feeding fuel thereto during the operation of the producer having an agitator playing freely vertically, an adjustable weight exerting downward pressure on the agitator and means causing relative horizontal motion between the agitator and the coal while gas is being produced therein.
